UNITED STATES PATENT OFFICE.

MORTIMER B. MILLS, OF CHICAGO, ILLINOIS, ASSIGNOR TO H. S. MILLS, OF OAK PARK, ILLINOIS.

ANNUNCIATOR APPARATUS.

1,027,749.

Specification of Letters Patent.

Patented May 28, 1912.

Application filed February 17, 1912. Serial No. 678,414.

To all whom it may concern:

Be it known that I, MORTIMER B. MILLS, a citizen of the United States, residing at Chicago, in the county of Cook and State 5 of Illinois, have invented a new and useful Improvement in Annunciator Apparatus, of which the following is a specification.

The object of my invention is to provide a construction of annunciator to coöperate 10 with a delivery-device for checks, or the like, under the control of the operator, and cause operation of the delivery-device to display the amount to be paid, or value, denoted on or by the check.

15 In the accompanying drawings, Figure 1 shows my improved machine by a view in vertical sectional elevation, the section being taken on line 1, Fig. 2; Fig. 2 is a section on the irregular line 2, Fig. 1 or Fig. 3; Fig. 3 20 is a section on the irregular line 3, Fig. 1, and Fig. 4 is a section on line 4, Fig. 3.

The entire mechanism is contained in a suitable casing 5 shown to be provided with a lock-equipped hinged lid 6 for convenient 25 access to the interior, as for filling magazines 7 with stacks of checks 8, shown in the form of disks. The magazines, of which three are shown, all being alike, though the number may be any desired, are suspended 30 at arms 9 on their upper ends, to hang pivotally from a rod 10 extending across the upper part of the casing near its upper end, and thus be adapted to be swung on their support for effecting, by swinging a magazine, delivery from it, as hereinafter described, through a lateral front discharge slot 11 at its lower closed end into a cup 12 formed or provided in the ledge-portion of the casing; the magazine also containing a 35 rear slot 11¹ in line with the slot 11.

40 Spring-retracted push-rods 15, one for each magazine, are reciprocably supported near their outer ends in the front wall of the ledge-portion 13 of the casing and at 45 their inner ends in a wall 16 rising in the casing from its base and having bent fingers 17 extending from its upper edge to register, each, with a slot 11¹ in a different magazine, carrying a stud 18 engaged by the 50 bifurcated end of a curved arm 19 extending upwardly from the respective rod 15, whereby pushing the latter inwardly will swing the magazine in a backward direction to enter the finger 17 in the path of a slot 55 11¹ into the latter to force the lowermost

check 8 from the bottom of the stack and thus deliver it to the cup 12. When the push-rod thus operated is released, its re-tracting spring 20 restores it and the magazine to normal position.

60

A particular use to which my apparatus is advantageously applicable as an annunciator, and one in connection with which my invention may be most readily explained would be in a barber-shop, where the barber, 65 after serving a customer, ordinarily hands him a check marked with the amount due for the service (say 15 cents for a shave, 25 cents for a hair-cut, or 40 cents for both shave and hair-cut) and which he takes to 70 the cashier and pays. The annunciator enables the cashier, by glancing at it from the cashier's desk, to verify the correspondence of the amount represented by the annunciator with that displayed by the check, as the 75 result of the operation to produce delivery of that check.

A bank of levers, 21, 22 and 23, corresponding with the number of push-rods, extends transversely across and over the latter 80 from the fulcrum-point of the levers, at 24, within the bottom part of the casing at its front side; and the levers are supported at their inner ends to work in horizontal guides 25 formed between a pair of parallel posts 85 26, adjacent to one of which rises from the casing-base a stop-rod 27 to extend across the bank of levers and limit their extent of laterally-displacing movement. A spring 28 (Fig. 2) bears, in opposition to the stop 90 27, against the inner side of each lever adjacent to its fulcrum; and each lever terminates at its inner end, beyond the bank of guides 25, in a laterally and forwardly projecting tongue 29, shown slightly 95 curved.

A stud 15¹ rises from one push-rod, but is only long enough to engage the lowermost lever 21 by pressing that push-rod inwardly; a stud 15² rises from the next push-rod and is of a length to engage the 100 opposing edges of the lowermost and intermediate levers; and a stud 15³ rises from the third push-rod and is of a length to engage the three levers by forcing inwardly that push-rod. These studs are disposed on the respective push-rods at progressively-increasing distances from the bank of levers in the direction toward the fulcrum 24, to produce the same extent of movement 105 of the lever or levers, whichever push-rod 110

may be operated. Adjacent to the inner ends of the levers is provided, on the base of the casing, a post 30 having an oblique head 30¹ provided on one end with a stop-stud 31, 5 and on its opposite end with a similar stud 32. On a bearing-plate 33 rising from the casing-base, adjacent to the post 30, and containing a vertical slot 34, is fulcrumed a bell-crank 35 having one, deflected, arm 10 terminating in a curved head 36 to extend normally underneath the tongue 29 of the lowermost lever 21; the bell-crank having a tail-piece 37 projecting from the opposite side of its fulcrum across the slot 34. The 15 other arm of the bell-crank has fulcrumed to it a lever 38 connected by a relatively-weak spring 39 with a side of the casing, and by a relatively-stiff spring 40 with a stud 41 on the bell-crank near the lever- 20 fulcrum. The lever 38 terminates at its upper end in a laterally-extending arm 38¹, shown to be provided on its display-face with the numerals 15, 25 and 40, properly spaced apart. This lever-arm is movable 25 across an annunciator-opening 43 provided in suitable position in the face of the casing, there to display one or the other of the aforesaid numerals according to the extent 30 of turning on its fulcrum the lever 38, as hereinafter described.

From the front of the casing project horizontally two stop-rods 44, 44, between which extends a handle 45 on a spring-pressed rock-shaft 46 journaled to extend in 35 the casing across its base and past the bearing 33, adjacent to which it carries a cam 47 to engage a lever 48 passing at its free end through the slot 34 from its fulcrum at 49, for engaging the tail-piece 37 to return 40 the lever 38 and bell-crank 35 to normal position after each operation of the machine, described as follows:

To effect the delivery of a check of any 45 denomination from a magazine, the proper push-rod is pressed. Thus, by pressing the rod controlling delivery from the magazine containing the stack of 15-cent checks, the arm 19 on that rod is actuated to swing 50 backwardly the magazine engaged by it and cause the respective finger 17 to push a check from the bottom of the stack into the cup 12. By this movement of that push-rod, its stud 15¹ encounters only the lowermost lever 21 in its path, turning it on its fulcrum to take the tongue 29 on its inner end 55 out of the way of obstructing the head 36 against rising. Thereupon the spring 39 turns the lever 38 to raise the head 36 until it strikes and is thus arrested by the next-higher finger 29, and that extent of movement of the lever is sufficient to carry the arm 38¹ thereon to a position relative to the opening 43 to register therewith and display through it the numeral 15, correspond- 60 ing with the denomination of the delivered 65

check. By then turning the rock-shaft 46 to encounter the cam thereon with the lever 48, the rise of the latter against the tail-piece 37 turns the bell-crank to withdraw the arm 38¹ to normal position, and likewise the head 36 from obstructing the tongue 29 on the lever 21, when the spring 28 controlling the latter restores it to normal position. If the middle push-rod be used to effect delivery of a 25-cent check 70 from the proper magazine, its stud 15² will actuate both levers 21 and 22 in the manner described, to enable the head 36 to rise until it strikes the uppermost finger 29 and consequently permit turning of the lever 38 75 far enough to display the numeral 25 at the opening 43; and if the push-rod carrying the stud 15³ be used to effect a check-delivery from the 40-cent magazine, that stud will turn the three levers 21, 22 and 23 to 80 divert all the tongues 29 from obstructing the head 36 and permit it to be raised by the spring 39 until arrested by encountering the stop 31. In each instance of operation, turning the shaft 46 will, obviously, return 85 the parts of the annunciator-mechanism to 90 normal condition.

The stop 32 arrests the lever 38 against undue extent of movement in the direction toward it. The purpose of the relatively- 95 strong spring 40 for connecting the lever 38 with the bell-crank 35, instead of forming it integral therewith, is to absorb shock. Thus, if the head 36 be operated to rise against the stop 31, the momentum of the 100 head would tend to carry the lever-arm 38¹ unduly far relative to the opening 43, and jar the mechanism; whereas, in the event of such encounter, the spring 40 will tend to absorb the shock and will retract the lever-arm 38¹ to proper registration of the intended number on it to be displayed, from the undue distance it may have been carried by momentum past the annunciator-opening.

What I claim as new and desire to secure 110 by Letters Patent is—

1. In an annunciator-apparatus, the combination with a casing provided with a display-opening, of a bell-crank having a stop-head on one arm, a spring-actuated lever 115 having a laterally-extending arm bearing a series of annunciating characters on its display-face, said lever being fulcrumed to the bell-crank to be turned for moving said arm, by the force of said spring, across said opening, a relatively-stiff spring connecting the lever with the bell-crank to cause them to turn normally together, means releasably engaging said head to normally lock the bell-crank against the force of said actuating 120 spring, and means for restoring said bell-crank to normal position, for the purpose set forth.

2. In an annunciator-apparatus, the combination with a casing provided with a dis- 125

play-opening, of a bell-crank having a stop-head and a tail-piece on opposite ends of one arm and a spring-actuated lever on its other arm provided with a laterally-extending arm 5 bearing a series of annunciating characters on its display-face, a slotted bearing to which the bell-crank is fulcrumed to be turned by the force of said spring to move said lever-arm across said opening, a lever 10 projecting at its free end through the slot in said bearing, a spring-retracted rock-shaft carrying an operating handle and a cam to coöperate with said last-named lever, and means releasably engaging said head to normally lock the bell-crank against the force 15 of said actuating spring, for the purpose set forth.

3. In an annunciator-apparatus, the combination with a casing containing a display-opening, of a spring-actuated lever having an arm bearing a series of annunciating characters on its display-face, said lever being fulcrumed to be turned by the force of said spring to move said arm across said 20 opening, a stop-head connected with said lever to turn therewith, a vertical series of spring-pressed levers extending at one end into the path of said head, and means for turning at will any number of said last- 25 named levers out of said path, for the purpose set forth.

4. In an annunciator-apparatus, the combination with a casing containing a display-opening, of a spring-actuated lever having 30 an arm bearing a series of annunciating

characters on its display-face, said lever being fulcrumed to be turned by the force of said spring to move said arm across said opening, a stop-arm connected with said lever to turn therewith, a vertical series of 40 spring-pressed levers extending at one end into the path of said head, a stationary stop in said path above said lever series, and means for turning at will any number of the levers of said series, for the purpose set 45 forth.

5. In an annunciator-apparatus, the combination with a casing containing a display-opening, of a spring-actuated lever having an arm bearing a series of annunciating characters on its display-face, said lever being fulcrumed to be turned by the force of said spring to move said arm across said opening, a stop-head connected with said lever to turn therewith, a vertical series of 50 spring-pressed levers extending at one end into the path of said head, a series of push-rods, one for each lever in said series, and studs projecting from the push-rods across said levers for turning them out of said path by operating said rods, the stud on one rod being of a length to engage only the lowermost lever in said series, and the studs increasing in length on the other push-rods to adapt them to engage progressively - increasing numbers of 55 said levers, for the purpose set forth.

MORTIMER B. MILLS.
